(57) **CLAIM**

The ornamental design for a vehicle taillight, as shown and described.

DESCRIPTION

FIG. 1 is a front left perspective view of a vehicle taillight according to the present invention.

FIG. 2 is a rear right perspective view of the taillight shown in FIG. 1.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines illustrate portions of the vehicle taillight that form no part of the claimed design.

1 Claim, 8 Drawing Sheets
